D19734

UNITED STATES PATENT OFFICE.

WILLIAM W. GOODWIN, OF BORDENTOWN, NEW JERSEY.

DESIGN FOR A GAS-RANGE.

SPECIFICATION forming part of Design No. 19,734, dated April 1, 1890.

Application filed January 31, 1890. Serial No. 338,785. Term of patent 7 years.

To all whom it may concern:

Be it known that I, WILLIAM W. GOODWIN, a citizen of the United States, residing at Bordentown, Burlington county, State of New Jersey, have invented a certain new and original Design for Gas-Ranges, of which the following is a full, clear, and exact description, reference being had to the accompanying drawing, forming a part of this specification.

5 My invention relates to gas-ranges; and it consists of the novel configuration of the same, as shown in the accompanying photograph, forming a part of this specification. Its principal features are the general form of the

10 whole in the shape of a parallelogram and with partitional divisions into two lower and

one upper chamber, the latter surmounting the former, which are open in front, with two doors arranged in different vertical planes, the top chamber having flat fret-work covering in sections.

I claim—

The design for a gas-range, substantially as shown and described.

In testimony whereof I have hereunto affixed my signature this 5th day of December, A. D. 1889.

WILLIAM W. GOODWIN.

Witnesses:

ANDREW ZANE,
H. T. FENTON.
